CLAIM

We claim the ornamental design for an autonomously driven vehicle, as shown and described.

DESCRIPTION

FIG. 1 is rear end view of a vehicle showing our new design; FIG. 2 is a rear top view of the vehicle; FIG. 3 is a side view of the rear of the vehicle; and, FIG. 4 is a perspective view of the rear of the vehicle. The environment illustrated in broken dot dot dash line in FIGS. 1-4 form no part of the claimed design.
